UNITED STATES PATENT OFFICE.

CHARLES E. WEHN, OF SAN FRANCISCO, CALIFORNIA.

PENCIL.

1,302,999.

Specification of Letters Patent.

Patented May 6, 1919.

Application filed December 3, 1918. Serial No. 265,094.

To all whom it may concern:

Be it known that I, CHARLES E. WEHN, a citizen of the United States, residing at the city and county of San Francisco and State of California, have invented new and useful Improvements in Pencils, of which the following is a specification.

This invention relates to a pencil, and particularly to that type which employs a removable and renewable lead.

One of the objects of the present invention is to provide a pencil which is simple and substantial in construction, cheap to manufacture, easy to manipulate and so arranged that the lead may be readily changed or replaced when worn. Another object of the invention is to provide means for advancing the lead, and particularly a novel form of screw feed mechanism for gradually advancing the lead as the point becomes worn. Further objects will hereinafter appear.

The invention consists of the parts and the construction, combination and arrangement of parts as hereinafter more fully described and claimed, having reference to the accompanying drawings, in which—

Figure 1 is a side elevation of the pencil.

Fig. 2 is a central longitudinal section through the same.

Fig. 3 is an enlarged cross section on the line 3—3 of Fig. 2.

Fig. 4 is an enlarged cross section on the line 4—4 of Fig. 2.

Referring to the drawings in detail, A indicates in general the pencil, which, in this instance, consists of a hollow cylindrical shell 2 and a solid end 3 which is pointed, as shown at 4, and provided with a central passage 5 for the reception of a lead 6. Formed on the opposite end of the pencil is a thread for the reception of a screw cap 7, which also serves as a holder for an eraser 8.

Formed within the shell, as at 9 and 10, are a pair of bearing members for the reception of a screw rod 11. Formed on the outer end of the rod is a flattened portion 12 which extends through a similar-shaped slot 13 formed in the bearing member 10. The flattened portion 12 serves the function of guiding the screw and simultaneously locks the screw against turning movement when it is advanced or retracted by means of a nut 14 which is interposed between the bearing 9 and the solid end of the pencil 3. The nut 14 is rigidly locked against end-

wise movement by the solid portion 3 and the bearing member 9. It is, however, free to turn as the sides of the nut are exposed, due to the fact that a pair of oppositely disposed oval slots 15 are cut in the cylindrical shell at points intermediate the bearing 9 and the solid end portion 3.

A pencil designed as here shown may be constructed of vulcanized hard rubber, metal or any other suitable material, and, as comparatively few parts are employed, it can be quickly and readily manipulated and should also be cheap to manufacture.

In actual operation, with the lead inserted in the pencil 5, it will only be necessary to turn the nut 14 to advance the screw 11, and, as this screw is positioned in alignment with the passage 5 and is adapted to engage the inner end of the lead, it should be obvious that it is possible to gradually force the lead outwardly through the point 4 of the pencil when the lead becomes worn away. The screw will not be able to turn when the nut 14 is manipulated due to the fact that the flattened portion 12 fits the slot 13 in the bearing 10. Furthermore, by flattening the end of the screw rod, as shown, it becomes possible to utilize the space in the upper end of the cylindrical shell as a magazine for extra leads, said leads being secured against accidental removal by the cap 7, which further serves as the holder for the eraser 8. The lead employed is forced into the passage 5 from the pointed end of the pencil and the passage is so small that it will frictionally secure the lead against dropping out.

It is therefore necessary when desiring to change a lead or to advance the same to turn the nut so that the screw rod will advance and force the lead outwardly. The nut 14 is designed to fit the interior of the shell and, as this is comparatively thin, it can readily be seen that the slots 15 through which the nut is manipulated will not necessarily have to be very large. Furthermore, it will be impossible to lose the nut as it is secured against endwise movement and is too large to become displaced by passing through the slots. The only removable members are the cap 7 and the screw rod 11.

While a more or less specific design and construction are here shown, I wish it understood that this may be changed to suit varying conditions. Similarly, that the ma-

terials and finish of the several parts may be such as the experience and judgment of the manufacturer may dictate.

Having thus described my invention, what I claim and desire to secure by Letters Patent is:

1. A pencil including a shell, a pair of spaced members in the shell one having an aperture and the other a non-circular aperture, an extension on one end of the shell having a lead receiving passage and having its inner end arranged adjacent to and spaced from one of said members, a threaded rod extending through said member having the aperture and having a portion conforming to and slidable through the member with the non-circular aperture, and a nut on the rod mounted between the first named member and the inner end of the extension.

2. A pencil including a shell, a pair of spaced members in the shell one having an aperture and the other a non-circular aperture, an extension on one end of the shell having a lead receiving passage and having its inner end arranged adjacent to and spaced from one of said members, a thread-

ed rod extending through said member having the aperture and having a portion conforming to and slidable through the member with the non-circular aperture, and a nut on the rod mounted between the first named member and the inner end of the extension, said second named member being spaced from the opposite end of the shell to provide a wall to permit leads to be stored in the shell and to engage said leads to restrict movement thereof within the shell.

3. A pencil including a shell, a lead engaging threaded rod in the shell, a nut for advancing the rod, a member in the shell, and means between the rod and member to hold the rod against turning, said member being spaced at such distance from an end of the shell to permit leads to be stored in the shell and to engage said leads to restrict movement thereof within the shell.

In testimony whereof I have hereunto set my hand in the presence of two subscribing witnesses.

CHARLES E. WEHN
